UNITED STATES PATENT OFFICE.

THEODORE DANHEISER, OF NEW YORK, AND FREDERICK FRANCIS FECHER, OF BROOKLYN, NEW YORK, ASSIGNEES TO THE BECK DUPLICATOR COMPANY, A CORPORATION OF NEW YORK.

DUPLICATOR.

1,422,934.

Specification of Letters Patent.

Patented July 18, 1922.

Original application filed October 11, 1917, Serial No. 196,040. Divided and this application filed November 22, 1920. Serial No. 425,885.

To all whom it may concern:

Be it known that we, THEODORE DANHEISER, a citizen of the United States, and a resident of the borough of Manhattan, in the city and State of New York, and FREDERICK FRANCIS FECHER, a citizen of the United States, and a resident of the borough of Brooklyn, in the city and State of New York, have invented certain new and useful 10 Improvements in Duplicators, of which the following is a specification.

The invention relates to duplicators, more particularly to that form of duplicator in which a negative or reversed impression of matter to be copied is impressed upon a duplicating surface, and positive impressions taken therefrom by bringing sheets of paper or the like in contact therewith; and has for one of its principal objects to provide simple and comparatively cheap means whereby the rapid handling of said sheets of paper is facilitated, this application being a division of application No. 196,040, filed October 11, 1917.

25 The invention consists in the novel construction, arrangement and combination of various devices, elements and parts, as set forth in the claims hereof, one form of the same being shown in the accompanying 30 drawings and hereinafter more particularly described.

In the said drawings, Fig. 1 is a side view of one embodiment of our invention; Fig. 2 is a longitudinal vertical section taken on the line 2—2 of Fig. 3 and looking in the direction of the arrows; Fig. 3 is an end view looking from the left of Fig. 1; and Figs. 4, 5 and 6 are views of the portion of the apparatus shown at the left of Fig. 2, 40 showing the parts in various positions.

In carrying our invention into effect in the embodiment thereof which we have selected for illustration in the accompanying drawings and description in this specification, we provide a duplicator of the usual or any suitable type, such as may comprise a base 11 having mounted thereon frame members 12, in which are suitably removably journaled rollers 13 upon which a duplicating film 14 is adapted to be wound. The duplicating film 14 passes upward and over a bed 16 secured between the members 12, rollers adjacent the ends of this bed being adapted to prevent the film from scrap-

ing against the said ends when the rollers 13 are rotated.

Suitable means for rotating the rollers 13, and means for either holding the same against rotation, or permitting such rotation, may also be provided; which means 50 may consist in a crank 17 adapted to be engaged with either roller, ratchets 18 operatively connected with the said rollers 13, pawls 19 adapted to engage with said ratchets, and devices 20 adapted, when desired, to hold said pawls out of operation; all of which means are now known in the art and need not be described in detail. It is thus possible to bring any portion of the duplicating film wound upon the rollers 13 70 into operative position over the bed 16, and to stretch the same tightly thereover.

A paper support or table is slidably mounted on the duplicator by means of flanged members 43 attached to said table 75 (see Fig. 3). The table comprises a bottom 40, an end 41, and sides 42 projecting beyond the left hand end of the bottom 40 as shown in Figs. 1 and 2. Pivoted at 43' in the free ends of these sides 42 is a U-shaped 80 frame 44 provided with a handle 45, and having an impression roller 46 journaled in its lower end.

At one side of the frame 44 is secured a laterally extending finger 47. A paper support or shelf 48 is pivoted at points 49 on the frame 44, and is provided on one side (see Fig. 1) with a slotted arc-member 50 by means of which its position may be adjusted, the member 50 being secured in any 90 position desired by means of a screw or the like 54. A paper depressing member 51 is secured to the frame 44, which depressing member 51 may if desired be, but is not necessarily, a roller. Means 52 may be provided for the purpose of restricting the operative area of the bottom 40 of the paper support or table.

In the operation of this embodiment of our invention, the attachment being in place 100 upon the duplicator, and the parts in the position shown in Figs. 1 and 2, a sheet of paper bearing the matter which it is desired to copy is placed face downward upon the table, and upon this are placed any desired 105 number of sheets of paper upon which it is desired to copy the matter transferred from the original to the duplicating medium,

so that one end of the pile shall rest upon the support 48, the devices 52 being adjusted in the proper manner. The handle 45 is then moved toward the right in Fig. 1, until the devices occupy the position shown in Fig. 4. When in this position the finger 47 enters a depression 153 in the bed 16, or may clear the end of the said bed, and the depressing member 51 forces the pile of paper downward, so that the sheet on the bottom of the pile will be brought into contact with the duplicating surface and will adhere thereto. The parts are then moved into the position shown in Fig. 5, leaving the sheet on the bottom of the pile adhering to the duplicating surface at one end, the remaining sheets being in their original position. The handle 45 being held in the position shown in Fig. 5, the attachment as a whole is moved toward the right in Fig. 1, withdrawing the undermost sheet of paper of the pile from the support or table, and bringing same into contact with the duplicating medium, whereby an impression is transferred from said sheet to said medium by means of the impression roller 46. After the attachment has been moved to its extreme right hand position, and approximately all of the paper has been passed over by the impression roller, the handle 45 and attached parts are moved into the position relative to the horizontal shown in Fig. 6, in which position the impression roller 46 is raised above the paper, enabling the said paper to be removed. The handle 45 being held in the position shown in Fig. 6, the attachment is returned to its original position, the finger 47 bearing upon the bed 16 and holding the paper depressing member 51 out of contact with the duplicating medium. The attachment being returned to the position shown in Fig. 4, the process may be repeated as often as desired, in this case, however, resulting in transferring impressions from the duplicating medium to the blank sheets of paper.

The advantages of our invention will be obvious. We may particularly enumerate the cheapness of construction, the ease of operation, and the fact that each impression will be printed upon the same relative portion of its respective paper. We do not limit ourselves to the exact form described, as it will be evident that various other modifications might be made, without departing from the spirit and scope of the said invention.

Having thus described our invention, what we claim as new and desire to secure by Letters Patent is as follows:

1. An attachment for duplicators adapted to be movably supported thereon and comprising means adapted to support parts of a plurality of sheets of paper or the like and to permit a part of the lower of said sheets

to be depressed on the said duplicator and adapted when moved with reference to said duplicator to permit said lower sheet to escape but to retain all the other said sheets; said attachment also comprising means adapted to so depress said paper.

2. An attachment for duplicators comprising a paper supporting member adapted to be movably mounted over a duplicator, and a frame secured to said paper supporting member, said frame being provided with a paper depressing member and with an impression device.

3. An attachment for duplicators comprising a paper supporting member adapted to be movably mounted over a duplicator, and a frame pivotally secured to said paper supporting member, said frame being provided with a paper depressing member and with an impression device, said impression device and said depressing member being located on opposite sides of said pivotal point.

4. An attachment for duplicators comprising a paper supporting member adapted to be movably mounted over a duplicator, and a frame secured to said paper supporting member, said frame being provided with a paper depressing member, an impression device, and a laterally extending finger adapted when said frame is in one position to come in contact with a portion of said duplicator, and when said frame is in another position to clear said duplicator.

5. The combination with a duplicator comprising a duplicating medium adapted to receive an impression and to transfer same; of a member movably supported on said duplicator comprising means adapted to support the marginal portions of a plurality of sheets of paper or the like and to permit a portion of the lower one of said sheets intermediate said marginal portions to be depressed into contact with said duplicating medium and adapted when moved with reference to said duplicating medium to permit said lower sheet to escape but to retain all the other said sheets; and devices adapted to depress a portion of said paper into contact with said duplicating medium.

6. The combination with a duplicator; of an attachment therefor comprising a paper supporting member adapted to be movably mounted over said duplicator, and a frame secured to said paper supporting member, said frame being provided with a paper depressing member and with an impression device.

7. The combination with a duplicator; of an attachment therefor comprising a paper supporting member adapted to be movably mounted over a duplicator, and a frame pivotally secured to said paper supporting member, said frame being provided with a paper depressing member and with an impression device, said impression device and

said member being located on opposite sides of said pivotal point.

8. The combination with a duplicator; of an attachment therefor comprising a paper supporting member adapted to be movably mounted over said duplicator, and a frame pivotally secured to said paper supporting member, said frame being provided with a paper depressing member, an impression device, and a laterally extending finger adapted

5 when said frame is in one position to come in contact with a portion of said duplicator, and when said frame is in another position to clear said duplicator.

Signed at New York city, N. Y., by the 15
said DANHEISER the 8th day of October,
1920, and by the said FECHER the 16th day
of November, 1920.

THEODORE DANHEISER.
FREDERICK FRANCIS FECHER.
